H. P. BALL.
BURNER FOR VAPOR STOVES.
APPLICATION FILED FEB. 20, 1919.

1,389,614.

Patented Sept. 6, 1921.

UNITED STATES PATENT OFFICE.

HENRY PRICE BALL, OF BROOKLYN, NEW YORK, ASSIGNOR TO S. STERNAU & COMPANY, INC., OF BROOKLYN, NEW YORK, A CORPORATION OF NEW YORK.

BURNER FOR VAPOR-STOVES.

1,389,614.

Specification of Letters Patent.

Patented Sept. 6, 1921.

Application filed February 20, 1919. Serial No. 278,161.

To all whom it may concern:

Be it known that I, HENRY PRICE BALL, a citizen of the United States, and a resident of borough of Brooklyn, county of Kings, 5 city and State of New York, have invented a certain new and useful Burner for Vapor-Stoves, of which the following is a specification.

My invention relates to burners for vapor 10 stoves or lamps and more particularly to such forms of devices wherein alcohol in solid or liquid forms is employed as the fuel and is consumed in the receptacle in which it is vended.

15 The object of my invention is to provide a device which may be employed in conjunction with any open ended fuel holder, such as a can, and which may, by its position relatively to the fuel holder, produce a 20 flame of intense heat and rapid consumption of the fuel contents of the holder, or produce a flame of considerably less heat and a proportional decrease in fuel consumption.

25 A further object is to provide a device which will be simple in construction, cheap of manufacture, which will not get out of order, simple in operation, and which may be used in connection with existing solid 30 fuel lamps or stoves.

These and further objects will more fully appear in the following specification and accompanying drawings considered together or separately.

35 I have illustrated one embodiment of my invention in the accompanying drawings in which like parts in all of the several figures are designated by similar reference characters, and in which—

40 Figure 1 is a plan view of a solid alcohol lamp or stove with my invention associated therewith in the position to give a flame of reduced intensity.

45 Fig. 2 is a side elevation, partly in section of the same, the section being taken on the line 2 of Fig. 1.

Fig. 3 is a similar view illustrating the invention in reversed position to produce a flame of large size and intense heat.

50 Fig. 4 is a side elevation the burner showing a modification, and

Fig. 5 is a fragmentary plan view of the same.

In the drawings 1 designates a cylindrical 55 tubular member, which may be termed a

chimney. At one end the chimney is provided with an exterior, peripheral flange 2. The flange is preferably dished as shown although this is not necessary to the operation of the device. The flange may be secured to the chimney in any desired manner, or it may be integral therewith.

Extending radially from the flange 2 is an arm 3 which is riveted or otherwise secured to the flange. The outer or free extremity of the arm carries a knob or handle 4 which may be of heat insulating material or of such a construction that it will not readily become heated.

Between the flange 2 and the opposite 70 end of the chimney is a series of radially projecting fingers 5. The fingers are preferably three in number, equally spaced apart, and may be formed by cutting U-shaped slits in the wall of the chimney and 75 bending the strips produced thereby outward at right angles to the wall of the chimney. The extremities of the fingers are preferably bent slightly, as shown at 6, in the direction away from the flange 2.

80 Preferably the chimney 1, flange 2, and arm 3 are made of sheet metal but I desire to have it understood that the device may be of cast metal, in which case the openings produced by the bending outward of the 85 fingers 5 will be omitted, or the device may be partly of sheet material and partly of cast material, or it may be made in any other desired manner.

86 The device of the invention is adapted to 90 be used in connection with a cylindrical, open-ended receptacle 7 such as is shown in my Patent No. 1,268,786, of June 14, 1918, but I desire to have it understood that the invention may be employed in connection 95 with any open ended container, and may with slight and obvious modifications be used with lamps or stoves of other than cylindrical shape.

96 Figs. 4 and 5 illustrate a modification in 100 which the device is made of cast metal, with the chimney 1^a, flange 2^a, fingers 5^a, and handle arm integral. The flange may be provided with a series of openings 8 for a purpose to be hereinafter described.

105 When the burner is in the position shown in Figs. 1 and 2 the flange 2 will rest upon the annular insert 9 in the top of the can and its periphery will rest within the top of the can as shown. When the fuel 10 preferably 110

solidified alcohol, is ignited the air to support combustion will be drawn in through the chimney 1 and the flame rising through the opening will restrict the opening whereby the amount of air for supporting combustion will be reduced.

As the level of the fuel recedes the flame will remain in the upper part of the can because of the small supply of air which will be consumed in the vicinity of the then lower edge of the chimney 1 which is approximately at the level of the top of the can. The heat of the flame will, however, be sufficient to vaporize the alcohol content of the fuel even to the last drop.

The flame issuing from the top of the chimney will be small and will give off a relatively small amount of heat. The vaporizing of the alcohol will be slow whereby economy of operation may be attained.

When the burner is reversed to the position shown in Fig. 3, the fingers 5 will rest upon the insert 9, the lower end of the chimney will extend into the can, and the flange 2 will be at the upper end of the chimney. Air to support combustion will enter the annular space between the chimney and the insert. When the fuel is ignited flame will, because of the abundance of air admitted through the annular opening, rise to a considerable height above the top of the chimney and will fill the entire cross sectional area thereof.

The heat given off will be intense and the fuel consumption will consequently be rapid. As the level of the fuel recedes the flame will follow the surface thereof and combustion will take place before the alcohol vapor can rise to any considerable extent. This is made possible by reason of the shape of the chimney and of the annular opening between the same and the insert. The annular opening will act as a nozzle and direct the inrushing air downward into the can. This action is materially assisted by the flange 2 which prevents the air heated by contact with the outside of the chimney from rising and the inrushing cold air will, together with the heated air, be forced downward into the can and support combustion at or near the surface of the fuel until it has all been consumed.

In use let it be assumed that boiling water is desired. The burner is placed in the position shown in Fig. 3, and the fuel lighted. A vessel containing water is now placed over the burner and a short distance above it. A large, hot flame will be produced which will spread all over the bottom of the boiler, and the water will be quickly brought to the boiling point or other desired temperature. If it is the intention to keep the water at a comparatively high temperature but below the maximum, the burner is removed from the can. The large opening

defined by the insert will permit of the entrance of air sufficient to support a flame of considerable size and heat.

If it is desired to keep the water merely warm, the burner is inverted and placed in the position shown in Fig. 2. The flange 2 will cut off the supply of air through the annular opening and the flame will be greatly reduced in size and intensity.

By the employment of the openings 8 in the flange 2^a the capacity of the device, when used in the position shown in Fig. 2, will be about midway between the maximum, and minimum.

In accordance with the provisions of the patent statutes I have described the principle of my invention, together with the apparatus which I now consider to represent the best embodiment thereof, but I desire to have it understood that the apparatus shown is merely illustrative, and that the invention may be carried out in other ways.

Having now described my invention what I claim as new and desire to secure by Letters Patent is.

1. A burner comprising a tube, a number of greater diameter than the tube at one extremity thereof and adapted to support the tube when the latter is in one position, and outwardly projecting means carried by the tube in proximity to the opposite end thereof, said means being adapted to support the tube when the latter is in the inverted position.

2. A burner comprising a tube, a member at one extremity adapted to support the tube when the latter is in one position, and a plurality of separated means carried by the tube in proximity to the opposite end thereof, said means being adapted to support the tube when the latter is in the inverted position.

3. A reversible burner comprising a tube, an outwardly extending peripheral flange at one extremity thereof and adapted to support the tube when the latter is in one position, and outwardly projecting fingers carried by the tube in proximity to the opposite end thereof, said fingers being adapted to support the tube when the latter is in the inverted position.

4. A reversible burner comprising a tube, an outwardly projecting flange at one extremity adapted to support the tube when the latter is in one position, a plurality of separated, outwardly projecting means carried by the tube in proximity to the opposite end thereof, said means being adapted to support the tube when the latter is in the inverted position, and a radially projecting handle carried by the burner.

5. A burner comprising a receptacle open at the top, a removable chimney associated with the opening, said chimney being of less diameter than the opening, and means car-

ried by the chimney for supporting the same by engagement with the top of the receptacle, there being an annular opening outside of the chimney for admitting air to the interior of the receptacle.

6. A burner comprising a receptacle open at the top, a removable chimney associated with the opening, said chimney being of less diameter than the opening, there being an 10 annular opening between the outside of the chimney and the wall of the receptacle for admitting air to the interior of the receptacle while the chimney is in position, and means carried by the chimney for supporting 15 the same by engagement with the top of the receptacle.

7. A burner comprising a receptacle open at the top, a removable chimney associated with the opening, said chimney being of less 20 diameter than the opening, means for supporting the chimney in the opening in the receptacle thereby forming an annular opening between the outside of the chimney and the walls of the receptacle for admitting air 25 to the interior of the receptacle, and means carried by and projecting outwardly from the chimney and over said annular opening.

8. A burner comprising a receptacle open at the top, a removable chimney associated 30 with the opening, said chimney being of less diameter than the opening, means for supporting the chimney in the open top in such a manner as to form an annular opening between the chimney and the walls of the 35 receptacle for admitting air to the interior of the receptacle, and means carried by the chimney for supporting the chimney and closing the receptacle except for the chimney opening when the chimney is in reversed 40 position.

9. A burner comprising a receptacle hav-

ing an opening at the top, a hydrocarbon fuel within the receptacle and adapted to be burned from the top, a reversible chimney being of less diameter than the opening, a 45 flange at one end of the chimney, said flange being of greater diameter than said opening whereby when the chimney is in position with the flange resting on the top of the receptacle there will be no communication 50 with the interior of the receptacle except through the chimney, supports carried by the chimney and spaced from the flange whereby when the position of the chimney is reversed and the supports engage the top 55 of the receptacle an annular space will be formed between the chimney and the opening, whereby air will be directed through the annular opening to support combustion in the receptacle, and a handle carried by 60 the chimney.

10. A burner comprising a receptacle having an opening at the top, a tubular member of less cross sectional area than that of the opening, means carried by the member for 65 supporting the member in the opening, said means being so proportioned as to allow a space between the exterior surface of the member and the wall defining the opening, the lower end of the member projecting below the top of the receptacle, and a flange carried by the member projecting outwardly therefrom above the space for directing air downward through the space around the member to support combustion in the receptacle.

This specification signed and witnessed Feb. 16, 1919.
